UNITED STATES PATENT OFFICE.

JOHN T. GILCHRIST, OF KNOBEL, ARKANSAS.

CAR-COUPING.

SPECIFICATION forming part of Letters Patent No. 312,345, dated February 17, 1885.

Application filed December 22, 1884. (No model.)

To all whom it may concern:

Be it known that I, JOHN T. GILCHRIST, a citizen of the United States, residing at Kno-
bel, in the county of Clay and State of Ar-
kansas, have invented certain new and useful
Improvements in Car-Couplings; and I do
hereby declare that the following is a full,
clear, and exact description of the same, ref-
erence being had to the annexed drawings,
making a part of this specification, and to the
letters and figures of reference marked there-
on.

Figure 1 of the drawings represents an end
view, in perspective, of a railroad-car, show-
ing my improved coupling-link connected to
the draw-head thereof; and Fig. 2, a detail
view, in perspective, of the coupling-link.

The present invention has relation to cer-
tain new and useful improvements in that
class of car-coupling links provided with lat-
erally-extending bars or rods to serve as han-
dles, as the object thereof is to improve the
construction, whereby the links will be much
stronger, less liable to bend or twist, and
more evenly balanced. These objects I at-
tain by the construction substantially as
shown in the drawings and hereinafter de-
scribed and claimed.

In the accompanying drawings, A repre-
sents the end of a car, having connected there-
to, in the usual manner, the draw-head B, to
which is secured the coupling-link C by pin a.
This link C is of the form shown in Fig. 2,
and is cast with handles D, extending trans-
versely or at right angles to the length of the
link, and are of sufficient length to project
some distance beyond the sides of the draw-
head, so that the link can be held in position
by one of its handles, while the draw-heads

come together without danger of injury to the 40
person coupling the cars. The rod or bar
which forms the handles D passes through the
link, which in reality divides it into inde-
pendent links c d, thus greatly strengthening
the coupling-link proper, allows less opportu- 45
nity of its twisting, and in many respects ren-
ders it more practicable. The draw-heads have
each grooves b at their outer end, to form seats
for the handles D and bring them flush with
the end of the draw-heads, so that when com- 50
ing together the handles will not be injured
by the draw-heads striking them.

Unlike the links heretofore employed, where
the transverse handle passes or extends from
the side of the link, and not through it, it will 55
be seen that the rod or bar forming the han-
dles in the present invention divides the link
into two independent links, thus strengthen-
ing it at a point where it most needs it, and
in many respects renders it more practical. 60

Having now fully described my invention,
what I claim as new, and desire to secure by
Letters Patent, is—

The combination, with the draw-heads of a
railroad-car having grooves at their outer
ends to form seats, and the usual coupling-
pins, of a horizontal bar or rod cast with in-
dependent links, said bar or rod extending
between the links and beyond each side there-
of to form transverse handles, substantially 70
as and for the purpose set forth.

In testimony that I claim the above I have
hereunto subscribed my name in the presence
of two witnesses.

JOHN T. GILCHRIST.
